CONTAINER CLOSURE CAP

Trevor Gwilym Evans, Welwyn Garden City, England,
assignor to Lever Brothers Company, New York, N.Y., a corporation of Maine

Filed Sept. 13, 1966, Ser. No. 3,833

Claims priority, application Great Britain Mar. 24, 1966

Term of patent 14 years

(Cl. D58—26)

I claim:

The ornamental design for a container closure cap, substantially as shown.
